UNITED STATES PATENT OFFICE.

ALEXANDER F. OKEY, OF SAN FRANCISCO, CALIFORNIA, ASSIGNOR TO
GEORGE K. BIRGE, OF BUFFALO, NEW YORK.

DESIGN FOR WALL-PAPER.

SPECIFICATION forming part of Design No. 24,898, dated November 12, 1895.

Application filed October 15, 1895. Serial No. 565,800. Term of patent 3½ years.

To all whom it may concern:

Be it known that I, ALEXANDER F. OKEY, a citizen of the United States, residing at San Francisco, in the State of California, have invented and produced a new and original Design for Wall-Paper, of which the following is a specification, reference being had to the accompanying drawing, showing a part thereof.

The design consists of a central fleur-de-lis ornament inclosed in an ornamental panel formed of ornamental scrolls springing from the base of the center ornament and fleur-de-lis ornaments outside of said ornamental scrolls and connected with said scrolls, as represented in the accompanying drawing.

The border of the design is formed of fleur-

de-lis ornaments with ornamental figures arranged between the fleur-de-lis ornaments and ornamental scrolls arranged below the fleur-de-lis ornaments and connected with inverted fleur-de-lis-shaped figures arranged below the oblong ornamental figures, as shown in the drawing.

What I claim is—

The design for wall paper herein shown and described.

Witness my hand this 9th day of October, 1895.

ALEX. F. OKEY.
